UNITED STATES PATENT OFFICE.

CHARLES W. HOLTZER, OF BROOKLINE, MASSACHUSETTS.

ELECTRIC GAS-LIGHTING APPARATUS.

SPECIFICATION forming part of Letters Patent No. 338,748, dated March 30, 1886.

Application filed May 12, 1884. Serial No. 131,144. (No model.)

To all whom it may concern:

Be it known that I, CHARLES W. HOLTZER, of Brookline, county of Norfolk, State of Massachusetts, have invented an Improvement in Gas-Lighting Apparatus, of which the following description, in connection with the accompanying drawing, is a specification, like letters on the drawings representing like parts.

10 My invention relates to a gas-lighting apparatus specially intended for what is known in the trade as "candle-burners," or long burners having a long tubular portion or shank surrounded by a white tube, which resembles a candle in appearance. The gas-lighting device is of that class in which a vibrating or oscillating arm constitutes one terminal of an electric circuit, and is brought in its vibratory movement into contact with and then disengaged from a stationary circuit terminal or electrode located in or near the gas issuing from the burner, which is lighted by the spark produced at the said electrode or circuit-closer.

15 25 It is frequently desirable to control the flow of gas by the same action that produces the spark; and this has been done with ordinary burners by means of a cock the spindle of which is concentric with or constitutes the pivot of the vibrating electrode, the said cock being engaged by and moved with the said electrode in the same movement by which the spark is produced.

20 30 35 Candle-burners have not been provided with the cock-operating devices, as it is impossible to inclose them in the candle-tubes, which are only large enough to receive the circuit-closer, and when the circuit-closers or spark-producing devices have been applied to candle-burners the latter have been tapped or bored, or otherwise especially constructed, to provide a pivotal support for the oscillating arm, so that in case the lighters are to be applied to burners already in use the latter have to be removed from their fixtures and taken to a factory or workshop to have the devices applied.

40 45 50 The present invention has for one of its objects to provide a lighting device that can readily be attached to the burner without changing the latter or removing it from the

chandelier or fixture, and also to provide cock-operating mechanism that can be used in connection with the lighting device on candle-burners.

55 My invention in electric gas-lighting apparatus consists in the combination of the burner-tube and oscillating circuit-closer pivoted thereon, with a fitting at the base of the said tube containing a cock and having its spindle 60 provided with a ratchet and a pawl and pawl-carrying arm loose on the said spindle and connected with the said circuit-closer, and a spring to restore the said arm to its normal position, as will be described.

65 70 75 When desired to have the gas-cock operated automatically with the lighting device, the said gas-cock and its automatic actuating devices are inclosed in the ornamental base which constitutes the socket for supporting the candle-tube, and the said cock-operating mechanism is operatively connected with the oscillating electrode, so that both move simultaneously.

75 80 85 The inclosing-tubes for candle-burners have heretofore commonly been composed of white porcelain or glass, which is somewhat translucent, so that when gas-lighting devices have been used between the burner-tube and the said inclosing imitation candle-tube the said devices have cast a shadow on the said candle-tube which can be seen from the outside, and gives a disagreeable appearance. It is also difficult or impossible to obtain candle-tubes of glass or porcelain of sufficiently uniform size to receive the gas-lighting devices without in some cases interfering with the operation of said devices. To obviate this difficulty, the candle-tubes are, in accordance with the present invention, made of metal enameled or 90 otherwise whitened or colored on its outer surface, to give the tube the appearance of a candle.

95 Figure 1 is an elevation of a gas-burner having lighting devices embodying this invention, the candle-tube and its ornamental base being removed; Fig. 2, an elevation of the burner with the candle-tube and ornamental base-piece in place thereon, and Fig. 3 a detail to be referred to.

100 The burner consisting, mainly, of a long slender tube, *a*, provided with a tip, *b*, and in-

closed in a candle-tube, *c*, Fig. 2, may be of usual construction, the said tube *b* being screw-threaded at one end for connecting it with the fixture in the usual manner. When the burner 5 is to be provided with gas-lighting and gas-cock-operating mechanism, the latter is contained in a fitting, *d*, which may be applied by merely unscrewing the tube *a* from the fixture and then screwing the said fitting *d* on 10 the fixture and the tube *a* on the said fitting *d*, as shown. The spindle *e* of the cock is provided with a ratchet, *f*, adapted to be engaged by a pawl, *g*, mounted upon a pin, *h*^o, of an arm, *h*, loose upon the said spindle and back 15 of the said ratchet, so that when moved in the direction of the arrow by means of the rod or wire *i*, connected with the said pin, the cock will at the same time be turned; but when the said arm *h* is moved back in the other direction by its retracting-spring *k* the cock will 20 not turn with it. The wire *i* is extended upward along the burner, and is connected with the short arm or projection *m* of the vibrating electrode *n*, pivoted upon a screw, *o*, connected 25 with a pivot-piece, *p*, (shown separately in Fig. 3.) consisting of a piece of flexible or sheet metal made tubular to embrace the tube *a*, and provided with ears or wings *p'*, which receive clamping-screws, by which the said tubu- 30 lar socket-pieces may be tightly clamped upon the tube *a*, which latter does not require any preparation to receive the said clamping-piece. The socket-piece *p* is provided with a boss, *p*³, to afford a sufficient pivotal bearing for the 35 vibrating electrode *n*, which is provided with the usual spring-tip co-operating with the electrode *r*, fixed upon the burner near the orifice for the gas, and insulated therefrom by suitable insulating material—such as asbestos fiber—interposed between it and the burner- 40 tube in the usual manner.

The cock-operating mechanism *f g h* is inclosed in an ornamental shell, *t*, constituting the socket for the candle-tube *c*, and the rod or 45 wire *i*, connecting the arms *h* and *m*, and the electrode or circuit-closer *n* are inclosed in the said tube *c*, so that none of the said devices are visible, to disfigure the burner or destroy its resemblance to a candle.

The candle-tube *c* is composed of metallic 50 tubing coated with white enamel, or otherwise colored to give it the appearance of a candle, the metallic tubing being of uniform bore and opaque, so that it may be applied to burners having the lighting devices without interfering with the operation of the said devices or showing their presence by a shadow. 55

The burner-tube *a* is provided with the usual collar or flange, *a'*, to support the candle-tube *c*, concentric with the said burner-tube, and the 60 said collar has a hole or notch to receive wire *i*.

I am aware that prior to my invention gas-lighting apparatus has been used in which an electrode fastened to a pivoted rod and provided with a spring acting between flanges to 65 restore the said rod to its normal position after each operation of the circuit-breaker has been employed, and I do not herein claim such an apparatus.

I am also aware that a gas-lighting apparatus 70 has been used in which the admission of the gas and the creating of a spark by which to ignite the gas were controlled by a cock provided with a pair of pivoted arms or cranks arranged on a disk or washer applied to the said cock 75 and connected by a non-conducting cord with a pivoted or vibrating finger; which construction I do not herein claim.

I claim—

In an electric gas-lighting apparatus, the 80 combination of the burner-tube and oscillating circuit-closer pivoted thereon with a fitting at the base of the said tube, containing a cock and having its spindle provided with a ratchet and a pawl and pawl-carrying arm loose on the said 85 spindle and connected with the said circuit-closer, and a spring to restore the said arm to its normal position, all substantially as described.

In testimony whereof I have signed my name 90 to this specification in the presence of two subscribing witnesses.

CHARLES W. HOLTZER.
